ABSTRACT

A cap device is coated externally and internally with a vaginal mucous membrane antiseptic and is formed of a water-soluble starch.

FIG. 1

FIG. 2

CONTRACEPTIVE MEANS

RELATED APPLICATION

This application is a continuation-in-part of application Ser. No. 878,232, filed Nov. 19, 1969 now abandoned.

The present invention relates to means applicable by male or female and having a mechanical, antiseptic and orthogenetic protective and preventive action, and to a method of producing such means.

As is generally known, the prevention of infection with diseases in sexual intercourse and also the necessity of a sufficient protection for eugenic reasons represent actual problems. Various means are already known which provide the effects referred to by mechanical or chemical means. Such means or agents comprise for example tablets, globules, pessaries, diaphragms, little sponges, tampons, creams and the like, which must be introduced into the vagina and which thus shift the severe responsibility for hygenics and also for the prevention of conception entirely to the female. This fact often causes psychic difficulties to the sensitivity of female emotions; in addition, often the aid of a third person must be asked, e.g. in case of introducing pessaries or diaphragms.

On the other hand, means applicable by the male are already known such as e.g. condoms which, however, being a foreign body, have the disadvantage of exerting an irritating and desensibilizing effect and of necessitating subsequent removal. In addition, therapeutic medicaments must also often be introduced into the vagina, against which necessity there exist again prejudices and psychic scruples.

In all birth-control methods, with the exception of abstention, a risk of varying degree is found either from the view point of efficacy or side effects.

Medical literature provides epidemiological data in respect of every contraceptive technique. Though frequently at variance with each other because of different statistical methods used, all conclude that none is free of failures or side-effects and that the efficacy of every contraceptive method depends largely on the social, psychological and cultural conditions of the individuals using them.

This accounts for the search for more innocuous and effective contraceptives, easy to apply, without interfering with sexual sensation, and acceptable from the economic point of view. A new contraceptive of the intra-vaginal type has now been developed for the purpose of achieving the ideal characteristics described above.

This pharmacological association of spermicidally and germicidally active substances is available in the form of "caps", which can be introduced into the vagina either by the male by application to the glans penis, or by the female to the os uteri, prior to sexual intercourse.

In accordance with the present invention, there is provided a contraceptive in the form of a cap or suppository having the shape of an ellipsoid of revolution adapted to either the shape of the glans penis or the os uteri and formed so as to cover all or part thereof. This cap comprises a shell of a cachet-type sheet of starch having an external surface layer A and an internal surface layer B.

The caps are illustrated in the drawings, wherein

FIG. 1 is a perspective view of a cap, and

FIG. 2 is a view of an enlarged section of the cap.

In the Figures, C is a cap the starch sheet C₁ of which contains external layer A on the outer surface thereof and internal layer B on the inner surface thereof.

5 The starch is a water-soluble starch such as described in L. Adam-Cachets Azymes et cachets medicamenteux — Paris 1928. The starch dissolves rapidly at the normal temperature of the human body (37°C.) and upon contact with the moist vaginal membrane. Ap- 10 proximately 40 percent of the starch of the cap dis- solves in water at 37°C. in about 5 minutes and about 100 percent so dissolves in about 10 minutes. For example, a cap can have a diameter of approximately 22-24 mm and a weight of about 40 mg.

15 External surface layer A comprises about 18-24 mg containing 80-90 percent of Tween 20 (a polyoxyethylene sorbitan monolaurate) and 10-20 percent of active medicinal substances.

Internal surface layer B comprises about 160-200 mg containing 80-90 percent of a mixture of excipients and about 20-10 percent of active medicinal substances. The excipient mixture contains water-soluble lanolin, talc and Tween 20, in relative weight ratios ranging from about 90:70:4 to 80:60:4, respectively.

20 25 In both layers A and B, the active medicinal substances comprise mixtures of phenylmercuric nitrate, benzethonium chloride and methyl p-oxybenzoate, the relative weight ratios being in the range of from 2:4:25 and to 3:5:20, respectively.

30 35 The caps according to this invention are superior to prior caps. The combination of the active substances mentioned above assures optimal medicinal action, while the nature and the proportions of the excipients assure other important advantages.

35 40 In particular, external layer A containing Tween 20 assures three advantages:

- a. to put a part of the active substances into immediate contact with mucous membranes;
- b. to delay by some seconds the softening of the starch cap in order that it may more easily reach its destination;
- c. to prevent the sheet from sticking immediately to mucous membrane of the vagina, as occurs with the common cachets.

45 50 Internal layer B containing water-soluble lanolin, besides serving as a vehicle for the remaining active substances, also acts as a paste or adhesive, allowing the cap to adhere to the glans penis or the os uteri on which it is applied.

55 60 The caps' stability under normal environmental conditions is optimal (after 2 months' exposure to normal environment, no alterations were observed). At 60°C., stability is still highly satisfactory. It is also good when exposed to a high degree of humidity.

The spermicidal activity of the caps has been shown on bulls' and men's sperm. The latter test (Baker's test) showed that one-eighth of a cap is sufficient to immobilize 4 ml. of human sperm within 5 minutes.

65 60 The absence of any local irritant activity of the caps has been confirmed by instillation in the conjunctival sack of a rabbit or by introducing it in the skin of a rabbit's ear.

Experiments have demonstrated the bacteriostatic and bactericidal activity of the caps on organisms including *Spirocheta pallida*, *Streptococcus cureus*, and *S. pyogenes*, *S. Lactis*, *Enterococcus*, *Pseudomonas pyocyannea* and *Trichomonas vaginalis*.

Intravaginal tolerance of the caps has been studied by introducing daily for 20 days a previously determined dose of the product in the vagina of 10 rabbits. No local reactions or irritation were observed macroscopically or microscopically. The tolerance of the caps was demonstrated in a preliminary trial in women by the daily introduction in the vagina of one cap for 20 consecutive days, as illustrated in EXAMPLE 3, below.

The following examples illustrate the invention.

EXAMPLE 1

On the external surface of caps consisting of starch sheet having a diameter of 24 mm (1 inch), a layer was applied having a weight of 20 mg consisting of a homogeneous mixture of the following compounds:

	mg
Tween 20	17
Active substances	3

Upon the internal surface of the same caps, a layer having a weight of 180 mg was applied consisting of a homogeneous mixture of the following components:

	mg
Water soluble lanolin	83.2
Talc	66.0
Tween 20	4.1
Active substances	26.3

The active substances, in both layers contain, in turn, a mixture having the following composition (in weight):

	parts
phenylmercuric nitrate	2.15
benzethonium chloride	4.55
methyl p-oxybenzoate	23.00

Phenylmercuric nitrate and benzethonium chloride are known to have bacteriostatic and bactericidal activity. A combination of the two substances is known to be more effective than either alone in arresting the activity of *Spirocheta pallida*, and is useful for the prevention and local treatment of venereal infection of the female genital organs.

EXAMPLE 2

The following tests were conducted in order to indicate the dissolution time of the starch caps such as those illustrated in EXAMPLE 1.

In order that the dissolution time of the caps could be better ascertained, a dye (Water-soluble Blue Re. Pi. Co.) was incorporated in the excipients, which dye had an absorption peak at 637 m μ . At determined intervals the dye concentration was read on a spectrophotometer. In each cap, 5 mg. dye were incorporated. Seven beakers containing exactly 100 ml. water were placed on a thermostatic water bath at 37°C. corresponding to body temperature. When the temperature had reached the equilibrium value, seven caps were added successively. The contact time with water was 1 - 3 - 5 - 7 - 9 and 11 minutes respectively, whereas for the 7th beaker, the complete dissolution of the dye was permitted. This latter test served as a comparison for establishing the percentage values. In order to facilitate a homogeneous dissolution of the dye, the water was stirred slightly during the test with a glass rod.

At the end of each of the above-predetermined periods, 10 ml. of the respective solutions were taken and added with 0.01 ml. 20% NaOH in order to set the pH of the solution and, therefore, stabilize the specific

absorption of the dye. After centrifugation, the extinction of each of the resulting solution was determined on a spectrophotometer.

The results are shown on the following page.

TABLE I.—RESULTS OBTAINED FROM FOUR TESTS

[The figures represent the spectrophotometric absorption at 637 m μ .]

		After (minutes)—						Total solution
		1	3	5	7	9	11	
10	1st Test.....	476	1,201	1,693	2,375	2,625	3,160	3,110
	2nd Test.....	425	1,247	1,676	2,390	2,595	3,035	2,900
	3rd Test.....	481	1,225	1,678	2,400	2,630	2,945	3,205
	4th Test.....	478	1,211	1,685	2,365	2,585	3,060	3,245
	Average....	465	1,221	1,683	2,382	2,596	3,050	3,115
15	Percentage values, percent	14.9	39.06	54.02	76.4	83.3	97.8	100

EXAMPLE 3

Clinical test data were obtained with starch caps having the following characteristics:

diameter	20 mm
external layer A	
Tween 20	17 mg
medicinal components	3 mg
internal layer B	
water-soluble lanolin	96.3 mg
talc	66 mg
Tween 20	4.1 mg
medicinal components	20 mg
the medicinal components of layers A and B	
phenylmercuric nitrate	2.05 mg
benzethonium chloride	4.25 mg
methyl p-oxybenzoate	17 mg

The rate of the dissolution of the caps at 37°C. (body temperature) has been calculated. About 40 percent of a cap is dissolved after 3 minutes and about 100 percent after 11 minutes.

Trials in humans were carried out in order to evaluate the contraceptive activity, side effects and degree of acceptability of the caps.

One hundred and five couples of volunteers known to be fecund, were interviewed prior to their participation in the trial. Of these, 11 couples renounced either because they did not trust the method, they preferred another, the husband was against it. In two of the couples pregnancy occurred before the test started. Of the remaining 94 couples, 30 accepted to use cap exclusively by male application, 58 exclusively by female application, while six varied the mode of application.

These couples were interviewed at regular intervals according to an established questionnaire, thus making it possible to collect information concerning the methods' acceptance or objections, the tolerance and side effects of the cap, and pregnancy. The answers collected during the course of the interviews concerning the acceptance of the method have been transformed into statistical data and those concerning the efficacy of the method have been calculated according to the method of Pearl (Human Biol. 4, 363, 1932), which expresses the "pregnancy index" for 100 years of exposure by the following formula:

$$R = \text{total number of conceptions by } 1200/\text{sum of months of exposure}$$

This index is considered more reliable for the study of the efficacy of contraceptives than simple percentages of success or failure.

None of the 94 couples who used the cap have reported any side effects, and it was well tolerated. There was a total absence of unpleasant sensations (such as burning, unctuousness, disagreeable odor, excessive

lubrification of the vagina, etc.).

Nine couples out of 105 refused to take part in the experiment. In comparison to other methods this represents an extremely low proportion of refusals (about 8 percent).

The acceptance was always excellent on the part of the 94 couples who used the product. All of them used the method for at least 2 months. 16 couples interrupted thereafter the use of the cap for the following reasons: 10 couples because they preferred another method, four because they did not trust this one and two because the husband was against it. 11 other couples did not continue use of the cap during the entire period allotted for the trial. Their motivation was not related to the method as such, but was due to a change of residence or because pregnancy occurred, as summarized in TABLE II below.

TABLE II
Efficacy of the cap

Mode of Use	Number of couples	Mean time of observation (in months)
male	30	9
female	58	8.7
mixed	6	11.8
Total	94	9.03

Mode of Use	Years of exposure	Number of pregnancies	Index of pregnancy
male	23	3	13
female	43	3	6.9
mixed	6	0	—
Total	71	6	8.4

As can be seen from TABLE II, six pregnancies occurred in the 94 couples who used the cap. There seems to be a slight difference between exclusively male and exclusively female application.

It is inherent in the nature of a limited clinical trial that there are limits in the sampling, the period of observation, etc. It, nevertheless, permits extrapolation of the trend of a phenomenon when a more extensive trial is conducted. As this cap, which is entirely new, has obtained a high index of acceptance without causing any known side effects, its contraceptive efficacy can be assessed by comparing the results of the trial with reported results obtained with other contraceptive means. This comparison is shown in TABLE III, below.

TABLE III

Means	Number of couples	Mean time of observation (in months)	Years of exposure	Pregnancy	Index of pregnancy
Cap	94	9	71	6	8.4
Condom	387	20	649	72	11
Diaphragma + gelatin	541	11	503	87	17
Gelatin only	291	15	354	39	11
Periodic continence	409	18	606	87	14
Interruption	—	—	—	—	18
Foam tablets	74	18	108	14	13
Suppositories	333	13	212	57	27

It is evident that the data are not statistically comparable for several reasons (different number of tests, different sites of application etc.). It is nevertheless possible to deduce from TABLE III a trend in favor of the cap of this invention, as its pregnancy index is the lowest, i.e. the most favorable.

This comparison does not comprise the pill, which is the most effective contraceptive. Numerous authors

agree in stating that the pill is effective in practically 100 percent of cases. It should, however, be observed that against these advantages side effects of the pill are described in numerous publications. In addition to these undesirable side effects there are other harmful effects: recent publications indicate on the bases of statistical analysis that the increase in the use of the pill had led to an increase in venereal diseases. This information based on epidemiological studies carried out in the countries where the pill has been freely available for many years, is attributed to the fact that women feeling safe from the fear of pregnancy, pay less attention to venereal diseases, which do not cause in the female a particularly severe subjective symptomatology.

In contrast to the starch caps of this invention, gelatin and polyvinyl alcohol caps have been proposed earlier. Gelatin, however, is substantially inferior to starch in: being substantially less resistant to heat; tends to harden and becomes less soluble with time; substantially slower in going into solution; and, while dissolving in the vagina, it gives a sensation of being greasy or slippery and is substantially less desirable aesthetically. Similarly, polyvinyl alcohol has the following disadvantages, not shared with starch: not tolerated by sensitive persons, tends to form lumps which dissolve slowly; less resistant to external stress and less stable with time; less readily and less comfortably inserted into the vagina.

We claim:

1. In a contraceptive in the form of a shell-shaped cap device adapted to conform to the glans penis or the os uteri, and having elastic consistency and melting properties in the female vagina, said cap having applied on the external surface thereof an external layer (A) functioning to put active substances thereof into immediate contact with mucous membranes of the vagina, and said cap having applied on the interior surface thereof an internal layer (B) functioning to allow the cap to adhere to the glans penis or the os uteri to which it is applied and to carry the remaining active substances, the improvement which comprises

said cap device being formed from a cachet-type sheet of starch, about 40 percent of which dissolves in water at 37°C. in about 5 minutes, and about 100 percent of which so dissolves in about 10 minutes, a coating defining said external layer (A) on said external surface comprising from about 80 to about 90 percent by weight of polyoxyethylene sorbitan monolaurate, and from about 20 to about 10 percent by weight of a vaginal mucous membrane medicament,

a coating defining said internal layer on said inner surface comprising from about 80 to about 90 percent by weight of water-soluble lanolin, talc and polyoxyethylene sorbitan monolaurate as an excipient and from about 20 to about 10 percent by weight of the said vaginal mucous membrane antiseptic medicament,

and
said vaginal mucous membrane antiseptic medicament comprising a mixture of phenyl-mercuric nitrate, benzethonium chloride and methyl polyoxybenzoate having a relative weight ratio of from about 2:4:25 to about 3:5:20, respectively.

2. A device of claim 1 wherein the excipient of said inner surface coating comprises a water-soluble lanolin, talc and polyethylene sorbitan monolaurate having a relative weight ratio of from about 90:70:4 to about 80:60:4.
